(57) CLAIM

The ornamental design for a kitchen wrap holder, as shown and described.

DESCRIPTION

FIG. 1 is a top front perspective view of my design for a kitchen wrap holder;

FIG. 2 is a top rear perspective view thereof;

FIG. 3 is a bottom perspective view thereof;

FIG. 4 is a front view thereof;

FIG. 5 is a bottom view thereof; and,

FIG. 6 is an enlarged side view thereof, the opposite side being a mirror image thereto.

The broken line portion of FIG. 1 is included to show unclaimed subject matter only and forms no part of the claimed design.
